US00D862385S

(12) **United States Design Patent** (10) Patent No.: **US D862,385 S**
(45) Date of Patent: ** Oct. 8, 2019

(54) **MULTI-PORT ADAPTER**

(71) Applicant: **SARIANA, LLC**, San Diego, CA (US)

(72) Inventors: **Alan Turksu**, San Diego, CA (US);
Mustafa Burak Guclu, San Diego, CA (US)

(73) Assignee: **SARIANA, LLC**, San Diego, CA (US)

(**) Term: **15 Years**

(21) Appl. No.: **29/626,748**

(22) Filed: **Nov. 20, 2017**

(51) LOC (12) Cl. **13-02**

(52) U.S. Cl.

USPC **D13/108**

(58) **Field of Classification Search**

(57)

CLAIM

The ornamental design for a multi-port adapter, as shown and described.

DESCRIPTION

FIG. 1 is a front, top, right perspective view of a multi-port adapter showing our new design;

FIG. 2 is a rear, top, right perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines in the figures represent portions of the article which form no part of the claimed design.

1 Claim, 6 Drawing Sheets
